UNITED STATES PATENT OFFICE.

ELLIS R. LEWIS AND DON J. COOK, OF KALAMAZOO, MICHIGAN.

DESIGN FOR A LAMP.

41,771.

Specification for Design.

Patented Sept. 12, 1911.

Application filed July 21, 1911. Serial No. 639,858. Term of patent 14 years.

To all whom it may concern:

Be it known that we, ELLIS R. LEWIS and DON J. COOK, citizens of the United States, residing at Kalamazoo, county of Kalamazoo, and State of Michigan, have invented a new, original, and ornamental Design for a Lamp, of which the following is a specification, reference being had to the accompanying drawing, forming a part hereof, which shows an elevational view of said design.

We claim:

The ornamental design for a lamp, as shown.

ELLIS R. LEWIS.
DON J. COOK.
